UNITED STATES PATENT OFFICE.

MORIS GERINGER AND ISIDOR GERINGER, OF NEW YORK, N. Y.

DESIGN FOR A FIXTURE ARM.

Application filed March 5, 1923. Serial No. 5,371. Term of patent 3½ years.

To all whom it may concern:

Be it known that we, MORIS GERINGER and ISIDOR GERINGER, citizens of the United States, and residents of the city of New York, county of Kings and county of New York, respectively, State of New York, have invented a new, original, and ornamental Design for Fixture Arms, of which the following is a specification, reference being had to the accompanying drawing, forming part thereof.

The figure is a perspective view of a fixture arm, showing our new design.

We claim:

The ornamental design for a fixture arm, as shown.

Signed at New York, in the county of New York, and State of New York, this 1st day of March, 1923.

MORIS GERINGER.
ISIDOR GERINGER.
